(57) **CLAIM**

The ornamental design for a support for a cargo ramp, as shown and described.

DESCRIPTION

FIG. 1 is a perspective view of a support for a ramp of a cargo plane, shown in an environment of use;

FIG. 2 is a perspective view of the support, shown removed from environment for clarity of disclosure;

FIG. 3 is a front and back perspective view of the support, shown removed from environment for clarity of disclosure;

FIG. 4 is a front and back plan view of the support, shown removed from environment for clarity of disclosure;

FIG. 5 is a left side and right side perspective view of the support, shown removed from environment for clarity of disclosure;

FIG. 6 is a left side and right side plan view of the support, shown removed from environment for clarity of disclosure;

FIG. 7 is a top view of the support, shown removed from environment for clarity of disclosure; and,

FIG. 8 is a bottom view of the support, shown removed from environment for clarity of disclosure.

The broken lines shown in FIG. 1 are illustrating an environmental structure and forms no part of the claimed design.

1 Claim, 8 Drawing Sheets
